EXPANDING FILE

Sol Scheinman, White Plains, N. Y.

Application February 25, 1937, Serial No. 127,621

8 Claims. (Cl. 129—15)

The present invention relates to files, and more particularly to files characterized by the capacity to expand or increase in size as the volume of the contents increases.

5 Expanding or accordion files made of heavy paper wherein the capacity to expand with increase in the volume of the contents is imparted to the file by a plurality of pleats or folds at the sides and bottom of the file or envelope are well known. These expanding envelopes are also provided with partitions which divide the interior thereof into a plurality of compartments. Both the plain and the partitioned expanding envelopes have enjoyed a wide use for a long time 10 largely because of their expansibility and adaptability for many purposes. They have, however, the drawback that they are necessarily made of relatively perishable material and in a short time they lose their original neat appearance. Also, 15 if one of these expanding envelopes has been filled to capacity with papers and the like, in which conditions the pleats or folds are almost straightened out, it becomes inconvenient to use them with contents of smaller volume because 20 25 the pleats have become flattened or distorted and are restored to their original condition only with considerable trouble.

So far as I am aware, the only attempt that has heretofore been made to increase the life of 30 these expanding paper files has consisted in applying strips of reinforcing material along the pleats, generally in the form of cloth tapes or the like. These reinforcements, however, are inadequate to increase the useful life of the envelope 35 for any considerable time, because they protect only portions of the envelope. Thus, while they reinforce the pleated sections of the envelope, they do not protect the original glazed or calendered surface of the envelope, nor do they prevent 40 the curling up of the edges of the flap which in a short time makes the file unsightly.

Metallic files are also known which are in the form of a box, the top or lid being pivoted so as to be capable of being swung open or closed; and 45 in which the front wall is pivoted so as to swing forwardly to make the contents more readily accessible. Files of this kind can be very durably constructed but their utility is limited because the front wall can be pulled forwardly for only a short distance as otherwise the contents of the file 50 will spill out. Also, as the file is opened, the contents tend to fall forward in a heap, making inspection of the contents and the insertion and removal of papers inconvenient.

55 I have found that by combining an expanding

or accordion type of envelope, or the essential parts thereof, with a metallic casing or file in a novel manner, as will be explained below, a structure of increased utility is obtained. By combining these two file structures each is made 5 to increase the utility of the other and there results a durable and convenient file which has the neatness and long life of the metal construction and at the same time the expansibility and wide adaptability of the accordion file. The 10 metal casing or file lends rigidity to and protects the expandable paper envelope; on the other hand, the envelope file enables the construction of the metal casing or file to be modified to permit the front wall to be swung forward to a greater extent, since the paper envelope or insert houses the contents and prevents their being spilled out or disarranged when the front wall of the casing 15 is swung downwardly. This increased amplitude of movement of the front wall makes the 20 examination of the contents easier than was heretofore the case with a metal file and also makes it more convenient to insert and remove papers.

My improved file construction is of particular 25 utility when a partitioned expanding envelope is employed, as the papers in the various compartments become readily accessible when the front wall is swung open, the individual compartments being all opened to substantially the same 30 extent so that the file can be manipulated and papers inserted or removed with only one hand; whereas with expanding envelopes as they are used today it is necessary to employ both hands to keep the envelope open and even then the 35 insertion and removal of papers is made difficult by the fact that the expanded envelope tends to contract as soon as it is released. With my improved construction the weight of the metallic front door acts to keep the paper envelope open 40 to the desired degree.

The present invention contemplates also the provision of means for moving the front wall of the casing to open position upon lifting of the 45 cover, as will be explained more fully below by reference to the accompanying drawings, wherein

Fig. 1 is a vertical section taken through my improved file in the closed position thereof;

Fig. 2 shows a side view of the file in the open 50 position;

Fig. 3 illustrates the manner of securing the back wall of the envelope insert to the rear of the casing and is taken along the line 3—3 of Fig. 1;

Fig. 4 is a view taken along the line 4—4 of Fig. 55

1 and shows the manner of securing the front wall of the envelope insert to the casing;

Fig. 5 presents a perspective view of a clamping plate for securing the insert to the front casing 5 wall;

Fig. 6 is a section on a smaller scale of a modified form of the invention with the insert removed to show the linkage mechanism for opening the front door of the casing upon lifting of the 10 cover thereof;

Fig. 7 shows the structure of Fig. 6 in the open position; and

Figs. 8 and 9 represent sections taken near the top and near the bottom, respectively, of the 15 modified form of envelope insert shown in Fig. 7, and shows the tapered character of the side wall pleats.

Referring to Fig. 1, the numeral 10 represents generically an outer casing which may be made 20 of metal, wood, cloth covered paper board, or other relatively stiff material, metal being preferred. The casing is composed of a front wall 11, a rear wall 12, a flat bottom wall 13 upon which file rests in the open and closed positions 25 thereof, side walls 13a and a cover 14. The cover is pivoted to the rear wall 12 as shown at 15 and the upper portions of the front and side walls are bent back upon each other to form a reinforced structure as shown at 16 and are inwardly offset to accommodate the rim of the 30 cover. As is shown in the drawings, the front, rear and side walls present an inwardly offset flange, extending completely about the casing in its closed position, such flange acting not only to 35 steady the cover, but to seal the contents of the file against the entry of dirt and other foreign matter, the cover fitting closely against such peripheral flange and extending for some distance above it to provide a space for index tabs and the like attached to the insert which will now be 40 described.

The rear flange 17 extends downwardly for a certain distance, shown at 18, for a purpose which will be described below.

45 The front wall 11 is pivotally mounted, as shown at 19, upon the bottom wall 10, so that, upon lifting of the cover 14 it can be swung forwardly, almost to the horizontal position as illustrated in Fig. 2.

50 The casing 10 is provided with a lining or insert shown in the form of an expanding or accordion folder or envelope 20, provided with a series of pleats 21 which enable the envelope to expand and contract as the file is opened and closed.

55 The envelope may be provided with partitions 22 which extend across the interior of the file and divide the latter into a number of compartments, the partitions being secured to the side pleats 21 and also to the bottom pleats 23, the envelope illustrated in Figs. 1 and 2 being one of conventional construction. The front double-ply wall 24, 24a of the insert is secured to the front wall 11 of the casing by means of a clamping plate 26 which has a lip portion 26a for engaging over 60 the front wall flange 16 and secures the insert wall against the front wall of the casing. The rear wall 25, 25a of the insert is secured to the rear wall of the casing by slipping it under the downwardly extending portion 18 of the rear wall flange 17, the rear wall being preferably secured 65 in position before the front wall. If desired, the clamping plate 26 may be permanently fixed to the front wall 11, similarly to the extension 18, but particularly when the insert of the casing is 70 to be frequently replaced upon becoming filled, it

will be found convenient to have the clamping plate 26 separate from the front wall as it then facilitates the insertion and attachment of the new insert.

The front wall 11 is provided with side plates 28, 5 which, together with the front wall, form a hopper which receives the forward portion of the opened envelope insert and protects the front and sides thereof against injury. The side plates 28 fit closely against the side walls 13a of the casing and are provided each with a circular slot 29 receiving a guide pin or stud 30 extending inwardly of the side walls 13a. The slots 29 serve to guide the movements of the front wall 11 and also limit the downward movement thereof to 15 avoid overstressing the paper insert.

As will readily be seen upon inspection of Fig. 2, the file in its open condition presents the expanding or accordion envelope in an expanded 20 condition in which the contents thereof are conveniently arranged for inspection. Because it is pivoted at its lower end to the bottom wall, the front wall 11 of the casing has an unusually large angle of opening, so that the insert is expanded to practically its full extent, the weight of the 25 front wall acting to keep the envelope or insert open, while the cover 14, at least to some extent, balances the weight of the material to the left of the pivot 19. It will be noted that even in the fully opened condition of the file the pleats 30 of the insert are for the greater part protected by the side walls 13a and the side plates 28 of the file. While the partitions 22 are not absolutely necessary, they are very desirable, because aside 35 from the fact that they divide the interior of the file into convenient compartments, they keep the contents of the file from falling forwardly in a heap when the front wall 11 is lowered. These partitions, in contrast to the known loose index or separating cards employed with steel 40 files having forwardly swinging front door portions, do not fall forward upon opening of the file, but, being held by the pleats, assume more or less uniformly spaced positions in which they afford ready access to the papers stored between 45 adjacent partitions.

In the construction shown in Fig. 6, parts corresponding to the parts of the structure of Figs. 1 to 5 are identified by the same reference characters. In this modified construction, means are 50 provided for causing positive opening of the file casing upon movement of the cover 14 to the open position. This automatic opening mechanism may take various forms and in the construction illustrated includes at each side of the casing, 55 a link 31 pivoted at 32 to the cover 14 and connected at its opposite end to a bell-crank lever 34 which is pivoted upon a fixed fulcrum 35 secured to the side wall. The other arm of the bell-crank lever is pivotally attached to a link 36 60 which is pivoted at 37 to one arm of a second bell-crank lever 38 which is pivotally mounted upon a pin or stud 39 fixed to the side wall. The other arm of the bell-crank lever 38 is attached at 41 to a link 39a which is pivotally connected with a 65 pin or stud 41 secured to the adjacent side plate 28. The side plates 28 may be provided with cut-outs 42 to receive the pins or studs 39 as the front wall 11 is raised to closed position.

Comparing Figs. 6 and 7 it will be seen that 70 upon opening of the cover 14 the link and lever mechanism 31, 34, 36, 38 and 39a is operated to exert an outwardly directed force against the side plates 28 and compels the front wall to open as the cover 14 is drawn back.

My improved file has further the advantage that it is not necessary to employ the expandible envelopes which are now in common use. In fact, a type of expanding envelope can be employed which is of simpler and cheaper construction than the known envelopes. An envelope can thus be employed which is expandible only at the sides, the bottom thereof being of fixed dimensions. This will be clear from the fact that when 10 encased in a steel casing the paper envelope does not expand in a direction normal to the surface of the front wall of the envelope, but rather in fanwise fashion, the bottom of the envelope remaining of fixed width, corresponding to the 15 width of the metallic (or cardboard) casing, while the upper portions of the file expand as the front wall of the casing is swung forwardly. The pleats along the sides of the envelope can thus be of tapered form, being narrowest at the bottom 20 and widest at the top, corresponding to the degree of expansion to which it is subjected at various heights as the front wall casing is opened.

This simplified insert construction is shown in Figs. 7, 8 and 9. As illustrated in Figs. 8 and 9, 25 which represent sections through a pleated side of the insert taken at a higher and lower point, respectively, the sides of the pleat increase in width, and hence the side wall as a whole increases in depth, toward the top of the insert, as 30 can be seen by comparing the pleat sides 44 and 43. By this construction, crowding at the bottom of the insert is avoided, and the absence of pleats in the bottom wall of the insert increases the capacity of the file, as no space is occupied by upwardly extending pleats. In fact, the bottom wall of the insert may even be entirely dispensed with.

It will be seen from the above that I have provided a combined file construction wherein a 40 lining or insert in the form of an expandible envelope is made very easily manipulatable by virtue of the fact that the rear wall is held to the rear wall of the relatively heavy outer casing, while the front wall of the insert or lining is held 45 in its extended position by the weight of the front wall of the casing and also by the weight of part of the contents of the file. It will also be noted that whereas in the ordinary use of an expanding envelope the degree of expansion is substantially 50 the same at both the top and bottom of the envelope, in my improved file construction the envelope is made to open in fanwise fashion which contributes greatly to the facility with which the 55 contents of the file may be examined. On the other hand, a modification of the construction of the outer casing is made possible by the presence of the expandible insert, the insert making it possible to pivot the front wall at approximately its lower edge and thereby increasing the usefulness 60 of the casing, for it then permits a wider angle of opening of the file.

Various modifications in the dimensions and arrangements of parts may be resorted to within the scope of the appended claims without departing 65 from the spirit of the invention.

I claim:

1. A file comprising an outer casing of relatively stiff material having a pivoted front wall adapted to be swung forwardly to expose the contents of the file, means for limiting the forward swinging movement of the front wall to a position short of the horizontal position, an expanding paper lining within the casing whose front and rear walls are attached to the corresponding walls 70 of the casing, the side portions being capable of

expanding and contracting as the front wall of the casing is opened and closed, the casing front wall being pivoted adjacent to the bottom wall of the casing, and a cover pivoted upon the rear wall of the casing and swingable rearwardly to 5 substantially the horizontal position to aid in counterbalancing the forwardly tilted front wall.

2. A file comprising an outer casing of relatively stiff material having a pivoted front wall adapted to be swung forwardly to expose the 10 contents of the file, means for limiting the forward swinging movement of the front wall to a position short of the horizontal position, an expanding paper lining within the casing whose front and rear walls are attached to the corresponding walls of the casing, the side portions being capable of expanding and contracting as the front wall of the casing is opened and closed, partitions extending between the side walls of the lining, and a cover pivoted upon the rear 15 wall of the casing and swingable rearwardly to substantially the horizontal position to aid in counterbalancing the forwardly tilted front wall and the contents of the forward compartments. 20

3. A file comprising an outer casing of relatively stiff material having front, rear, side and bottom walls and a cover pivoted upon the rear wall, the front wall being pivoted adjacent to the bottom wall of the casing and being provided with side plates having arcuate slots therein, 30 pins extending inwardly from the side walls of the casing and engaging within said slots to guide and limit the opening movement of the front wall, an expanding paper envelope having pleated sides and attached to the front and rear 35 wall of the casing, and partitions within the envelope dividing the same into a plurality of compartments, said envelope, upon opening of the front wall of the casing expanding in fanwise fashion to expose the contents of the individual 40 compartments, the cover being movable rearwardly to balance the forwardly tilted front wall and said slots being of such length as to limit the expansion of the envelope within the distorting point while yet permitting adequate expansion of the envelopes. 45

4. A file as set forth in claim 3, wherein the bottom of the expanding envelope is unpleated, and wherein the sections forming the pleats at the side of the envelope increase in width from 50 the bottom toward the top thereof, the depth of the pleated side walls increasing correspondingly from the bottom to the top.

5. A file comprising an outer casing of relatively stiff material having substantially rectangular rear, side and bottom walls and a pivoted front wall adapted to be swung forwardly to expose the contents of the file, and an expanding paper envelope within the casing whose front and rear walls are attached to the corresponding walls 55 of the casing but whose side portions are free to expand as the front wall of the casing is opened, the bottom of the envelope resting upon the casing bottom wall and being likewise of rectangular shape and of approximately the length 60 and width of such casing bottom wall, and the sides of the envelope being pleated and the sections forming the pleats increasing in width from the bottom to the top, the expansibility of the envelope thus likewise increasing from the bottom to the top. 65

6. A file comprising an outer casing of relatively stiff material having substantially rectangular rear, side and bottom walls and a pivoted front wall adapted to be swung forwardly to ex- 70

- pose the contents of the file, and an expanding lining within the casing whose front and rear walls are attached to the corresponding walls of the casing but whose side portions are free to
- 5 expand as the front wall of the casing is opened, said lining consisting of a paper envelope having pleated sides, the bottom of the envelope being substantially flat and non-expanding and of approximately the length and width of the casing
- 10 bottom wall, whereby crowding at the bottom of the envelope in the closed condition of the casing is avoided.
7. A file comprising an outer, protecting casing of relatively stiff material having a flat bottom
- 15 wall upon which the casing rests in the open and closed conditions of the file, a rear wall, a cover pivoted thereon and movable rearwardly to approximately the horizontal position, and a front wall pivoted to the forward edge of the bottom
- 20 wall, the front wall being adapted to be swung forwardly into inclined position to expose the contents of the file and into the substantially vertical position for closing the file, an expanding envelope housed within and protected by the
- 25 casing and having its front and rear walls attached to the corresponding walls of the casing, the sides of the envelope being capable of expanding and contracting as the front wall of the casing is opened and closed, the front wall
- 30 having rearwardly extending side plates protecting and concealing the lower portion of the envelope, means arranged to engage the side plates to limit the forward swinging movement of the

front wall to an inclined position, and partitions within the envelope and dividing the latter into a plurality of compartments, said partitions acting both to increase the accessibility of the contents of the file and to keep all of said contents except that adjacent to the front wall from bearing tiltingly against said wall in its open position.

8. A file comprising an outer protecting casing of relatively stiff material, including rigid rear, 10 side and bottom walls and a front wall pivoted adjacent to the bottom wall and provided with side plates and adapted to be swung forwardly to expose the contents of the file, means arranged to engage the side plates to limit the forward 15 swinging movement of the front wall to a position short of the horizontal position, and an expanding lining housed within and protected by the casing, the front and rear walls of the lining being attached to the corresponding walls of the 20 casing but the side portions thereof being free to expand as the front wall of the casing is opened, said casing including a cover, and lever and link mechanism fulcrumed on a side wall of the casing and connected to the cover and the front 25 wall in a manner to force opening of the front wall upon opening of the cover, said cover being connected to said lever and link mechanism in such manner as to be capable of being moved rearwardly substantially to the horizontal position on being opened so as to aid in counterbalancing the forwardly tilted front wall.

SOL SCHEINMAN.
